UNITED STATES PATENT OFFICE.

HAROLD P. BROWN, OF CHICAGO, ILLINOIS.

ARC AND INCANDESCENT LIGHTING SYSTEM.

SPECIFICATION forming part of Letters Patent No. 325,390, dated September 1, 1885.

Application filed January 8, 1885. (No model.)

To all whom it may concern:

Be it known that I, HAROLD P. BROWN, a citizen of the United States, residing in Chicago, in the county of Cook and State of Illinois, have invented a new and useful Improvement in Arc and Incandescent Lighting Systems, of which the following is a specification.

This invention relates to means for operating arc and incandescent lights from the same main circuit. In my invention a single shunt-circuit having an automatically-variable resistance is employed to compensate for such of the incandescent lamps in the parallel group as may not be in use; and the invention consists in arranging the several resistance-coils in parallel group, like the lamps, and in making each resistance-coil in the form of an electro-magnet to operate a switch for putting the next succeeding resistance-coil in the shunt-circuit when required. The tension of the springs connected with the armature-levers of these electro-magnets is so adjusted, by making each succeeding spring stronger than the preceding one, that the armature-levers will drop away in the reverse order, and thus cut the resistance-coils out of the shunt-circuit in the reverse order to that in which they are put in.

In the accompanying drawings, which form a part of this specification, and in which similar letters of reference indicate like parts, Figure 1 is a diagram view showing the arrangement of circuits embodying my invention. Fig. 2 is a detail plan view, partly in horizontal section, showing the arrangement of the resistance-coils; and Fig. 3 is a cross-section showing the same parts in elevation.

In said drawings, A may represent a dynamo-machine, or other source of electric energy; B, the main-circuit wire, in which may be arranged in series, in the usual manner, a number of arc-lamps, b. C is a local or incandescent-lamp circuit leading from the switch B', in which are arranged in parallel group a number of incandescent lamps, c, on the cross-wires c'; and D is a shunt-circuit leading from the point x, where the local and shunt circuit wires diverge, to the point x', where the same reunite. Arranged in parallel group in this shunt-circuit are a number of resistance-coils, d, corresponding

in number to the lamps in the parallel group, the resistance of each coil being equal to that of one lamp. Each of these resistance-coils 55 d is preferably made in the form of a double magnet and provided with cores d'. Each resistance-coil is connected by a cross-wire, d'', with the shunt-circuit wire D at one end, as at x² x², &c., and at the opposite end, through 60 a contact-piece, d³, and armature-lever d⁴, with the shunt-circuit wire, as at x³ x³. When the armature-lever is drawn up by force of the magnet, so as to make connection between the contact-piece d³ and the armature-lever d⁴, the 65 coil of the succeeding magnet will be put in the shunt-circuit in parallel. On a cross-wire, b³, leading from x⁴ to x⁵, is arranged an electro-magnet, E, whose coil e remains permanently in the lamp-circuit. This magnet E 70 is of high resistance, so that only a small fraction of the current will pass through it. The cross-wires c² from the first resistance-coil are connected through the contact-piece d³ and armature-lever d⁴ of this high-tension magnet, 75 so that the operation of the magnet E will make connection to put the first resistance-coil in the shunt-circuit. Each succeeding resistance-coil is put in the shunt-circuit by the electro-magnet of the preceding one operating 80 its armature-lever d⁴. The several armature-levers d⁴ are provided with springs d⁵, the tension of which is so regulated that the upper or last one of said armature-levers will always drop away from its magnet first, and the others in succession—that is to say, the spring for the first armature-lever is the weakest, the strength of the successive springs gradually increasing to the last. From each of the cross-wires d², as at x⁵, I lead a wire, d⁶, to the contact-points f f' f'', &c. These contact-points are all arranged together, so that a single contact maker or lever, F, may make connection at once with them all.

F' represents a low-resistance electro-magnet in the local circuit C, which operates to raise the contact making lever F, and thus break the connection, through the wires d⁶, with all the resistance-coils whenever current for one or more lamps is passing through the 95 local circuit C. The moment such current ceases, however, the armature-lever F will drop down upon the contact-points f f', and thus put all the resistance-coils in the shunt- 100

circuit, so that when the current is again turned onto the lamp-circuit C no injury can result either to any of the lamps or to any of the resistance-coils d , as would otherwise be likely to occur in case only one or two of the lamps or resistance-coils happened to be for the moment turned on or in circuit. The resistance-coils d may preferably be mounted on suitable spools, d^1 , and the cores d' , I provide with screw-threads d^2 , by which the whole may be secured to the heel-plate d^3 , which can be conveniently attached to the case G by a screw, g . Each armature-lever d^4 , I provide with a projecting arm or wire, d^5 , which overlaps the preceding armature-lever d^4 , so that it would be impossible for any armature-lever to drop away and break connection until after its immediately succeeding armature-lever has fallen back. The armature-lever d^4 , I prefer to make in the form of flat springs, and secure them to a curved or cam projection, d^6 , preferably by two screws, d^7 d^8 , so that the lower screw may serve to assist in the adjustment of the armature-lever. In this way I avoid the necessity of making a hinged joint for the armature-lever, which is more expensive, and at the same time I am enabled to adjust the armature-lever more delicately and make its action more perfect. The springs d^5 are provided with the usual adjusting screws, d^9 .

K is a post on which the adjusting-screw d^9 is mounted, and K' is another post, to which the stop-screw k is attached. The contact-piece d^5 is mounted on the post K'.

In operation, when one of the lamps in the parallel group is turned out, or happens from any cause to be extinguished, the resistance through the remaining lamps is, of course, increased, so that a greater portion of the current will take the course of the shunt-circuit D, and thus increase the force of the electro-magnet E, or of the core d' of the resistance-coil magnets, if any of them at the time be in the shunt-circuit, and thus draw up one of the armature-levers d^4 and make connection at one of the contact-pieces d^5 with the next succeeding resistance-coil, thus putting another resistance-coil in the shunt-circuit, and so on until the normal or proper amount of current is passing through both the lamps in the parallel group and the resistance coil or coils in the shunt-circuit. In case an additional lamp in the parallel group is lighted, it of course diminishes the resistance through the lamps, so that a greater fraction of the current will pass that way, and thus diminish the current passing through such resistance-coils as may be at the time in the shunt-circuit, thus weakening the electro-magnets until one (the last one) of the armature-levers d^4 drops away by action of the spring d^5 , thus cutting out one (the last one) of the parallel resistance-coils d of the shunt-circuit, and thereby increasing the resistance of the shunt-circuit to compensate for the additional lamp lighted in the parallel group. As each succeeding spring

d^5 is adjusted to be slightly stronger than its preceding one, the armature-levers will drop away one by one, thus cutting out the resistance-coils one by one, the last one added always being first to drop away.

I claim—

1. The combination of main circuit B with local or incandescent-lamp circuit C, having two or more incandescent lamps arranged in parallel group with the shunt-circuit D, having two or more resistance-coils, d , arranged in parallel group, switches connected with said coils, each resistance-coil forming part of an electro-magnet for operating the switch to put each succeeding resistance-coil in the shunt-circuit when required, substantially as specified.

2. The combination of local or incandescent-lamp circuit C, having a number of incandescent lamps arranged in parallel group, with shunt-circuit D, having two or more resistance-coils, each resistance-coil being provided with a core, d' , armature-lever d^4 , and contact-piece d^5 , whereby each succeeding resistance-coil may be put in the shunt-circuit by the preceding one, substantially as specified.

3. The combination of local or incandescent-lamp circuit C, having a number of incandescent lamps arranged in parallel group, with shunt-circuit D, having two or more resistance-coils, each resistance-coil being provided with a core, d' , armature-lever d^4 , and contact-piece d^5 , and springs d^5 for said armature-levers, each succeeding spring being stronger than the preceding one, whereby said armature-levers will be pulled back in the reverse order, substantially as specified.

4. The combination of local or incandescent-lamp circuit C, having a number of incandescent lamps arranged in parallel group, with shunt-circuit D, having two or more resistance-coils, each resistance-coil being provided with a core, d' , armature-lever, and contact-piece d^5 , each of said armature-levers being provided with a projecting arm, d^5 , overlapping its preceding armature-lever, so that said armature-levers must drop away in the reverse order to that in which they are pulled up, substantially as specified.

5. The combination of local or incandescent-lamp circuit C, having a number of incandescent lamps arranged in parallel group, with shunt-circuit D, having two or more resistance-coils, each resistance-coil being provided with a core, d' , armature-lever d^4 , and contact-piece d^5 , electro-magnet F', contact-making lever F, contact-pieces $f f'$, &c., and wires d^6 , connecting said contact-pieces with said resistance-coils, whereby all said resistance-coils will be put in the shunt-circuit whenever the current on the circuit C ceases, substantially as specified.

6. The combination of a series of three or more electro-magnets having armature-levers d^4 , each provided with an arm or projection, d^5 , overlapping its preceding armature-lever, so that said armature-levers must be drawn

back in their reverse order, substantially as specified.

7. The combination of a series of electro-magnets having armature-levers d^4 , provided with arms or projections d^8 , overlapping each preceding armature-lever, and springs d^9 , of gradually-increasing strength, so that said armature-levers will drop away in reverse order, substantially as specified.

10 8. The combination of local or incandescent-lamp circuit C, having two or more incandescent lamps arranged in parallel group, with shunt-circuit D, having two or more resist-

ance-coils, d , circuit-closing switches connected with said coils, each of said resistance-coils 15 forming part of an electro-magnet for operating one of said switches, and an electro-magnet, E, the coil of which is in parallel with the lamps for operating one of said switches to close said shunt-circuit D, substantially as 20 specified.
